Attorney

UNITED STATES PATENT OFFICE.

HERMAN H. BRANDES, OF CORYDON, KENTUCKY.

HEATER.

No. 817,900.

Specification of Letters Patent.

Patented April 17, 1906.

Application filed April 3, 1905. Serial No. 253,576.

To all whom it may concern:

Be it known that I, HERMAN H. BRANDES, a citizen of the United States, residing at Corydon, in the county of Henderson and State 5 of Kentucky, have invented certain new and useful Improvements in Heaters; and I do declare the following to be a full, clear, and exact description of the invention, such as will enable others skilled in the art to which it applies 10 pertains to make and use the same.

My invention relates to improvements in hot-air heaters for use in chimneys over open fire-grates, and particularly to that class of such devices by means of which hot air may be 15 supplied to one or more rooms of a house or building.

The object of the invention is to improve and simplify the construction of heating devices of this character, and thereby render 20 the same more efficient in use and less expensive to manufacture and install.

With the above and other objects in view the invention consists of certain novel features of construction, combination, and arrangement of parts, as will be hereinafter described and claimed.

In the accompanying drawings, Figure 1 is a front elevation of an open fireplace with my improved heater applied thereto, parts 30 being broken away to more clearly illustrate the construction. Fig. 2 is a vertical sectional view taken on the line 2 2 in Fig. 1, and Fig. 3 is a perspective view of the rear side of the heater removed from the fireplace.

Referring to the drawings by numerals, 1 35 denotes an open fireplace, 2 the usual grate mounted therein, and 3 my improved heater, which is disposed within the fireplace or chimney and above said grate. The heater 3 comprises a shell or casing 4, which is of substan-

tially rectangular form and has its front wall 5 inclined upwardly and inwardly, as shown. Arranged longitudinally within this closed hot-air casing at some distance above the 45 bottoms of its sides and ends is a transversely-curved baffle 6, which forms the bottom of said shell or casing. This baffle forms a substantially semicylindrical heat-retaining pocket or chamber 7 and is of less length and 50 width than the shell 3, so that hollow depending portions or legs 8 are formed at the lower end of the bottom of the shell 3. One or more cold-air-inlet pipes 9 open into these legs 8 at the rear and sides or ends of the shell 3, so 55 as to supply fresh air to the same at a point where the heat is greatest. One or more air

outlet or discharge pipes 10 lead from the upper portion of the shell 3 to carry off the heated air to any desired point. Any number of these pipes 10 may be provided, and 60 they may lead to any number of rooms in the house or building in which the heater is used. It will be understood that the cold-air-inlet pipes 9 may also lead to any point where 65 fresh air may be obtained. Extending vertically or downwardly through the shell or casing 3 is a smoke pipe or passage 11, which, as clearly shown in Fig. 3, is of rectangular form and of slightly-less length than the length of the shell 3. The lower end of the 70 smoke-passage 11 opens into the heat-retaining pocket 7 at its rear side, as shown at 12. In the upper portion of the smoke-passage 11 at a point adjacent to the top of the shell 3 is arranged a damper 13, which may be of any 75 desired form. As shown, this damper is in the form of a pivoted plate provided with an operating lever or handle 14. Arranged in the bottom of the shell or casing 3, immediately above the grate and beneath the pocket 80 7 and the lower end 12 of the smoke-passage 11, is a deflector 15, which is slightly curved 75 in cross-section and formed with longitudinal series of openings or perforations 16. These perforations are disposed directly beneath 85 the heat - retaining pocket 7, so that the smoke, gases, and products of combustion as they arise from the grate pass through said openings 16 and strike the reentrant surface 90 17 of the baffle 6 and are deflected downwardly into the lower end 12 of the smoke-passage 11. The front wall of the shell extends downwardly, as shown at 15^a, below the under side of the deflector 15, so that the smoke and gases will be prevented from passing 95 into the room.

The construction, use, and advantages of the invention will be readily understood from the foregoing description taken in connection with the accompanying drawings. It will be 100 seen that since the shell 3 is entirely air-tight and dust-tight the fresh air entering through the pipes 9 will become heated by reason of its contact with the heated surfaces of the legs 8, the baffle 6, and smoke-pipe 11 and 105 then pass off through the pipes 10 to the desired point without becoming contaminated by the smoke and gases from the fire. The provision of the baffle 6 within the shell 3 so as to form the heat-retaining pocket 7 and arrangement of the smoke-pipe 11, as shown, 110 greatly increases the efficiency of the device.

The damper 13, it will be understood, may be closed after the fire in the grate 2 has burned sufficiently to consume the smoke and other gases, so that the entire heat from the fire will 5 be utilized. In case more of the pipes 9 and 10 are provided upon the heater than are desired to be used suitable caps or closures may be provided upon the ends of those which are not to be used.

10 While I have shown and described the preferred embodiment of my invention, it will be understood that I do not wish to be limited to the precise construction herein set forth, since various changes in the form, proportion, and 15 the minor details of construction may be resorted to without departing from the principle or sacrificing any of the advantages of this invention.

Having thus described my invention, what 20 I claim as new, and desire to secure by Letters Patent, is—

1. A hot-air heater for open fireplaces, comprising a casing to be placed in a chimney and above a grate or burner, said casing having a 25 top, sides and a bottom, the latter having

openings, and a smoke-flue in the casing, extending upwardly therethrough, spaced from the rear and end walls thereof and having its lower portion formed by a baffle above the bottom of the casing and forming a heat-retaining pocket, said casing being provided with air inlet and outlet openings. 30

2. A hot-air heater for open fireplaces, comprising a casing having an air-heating chamber formed with a pocket at its lower side, a 35 flue extending through said chamber and open at its lower end into said pocket, and a baffle at the lower end of the flue and under the pocket and causing the draft to pass upwardly and forwardly under the baffle, into 40 the pocket, and from thence rearwardly into the lower end of the flue.

In testimony whereof I have hereunto set my hand in presence of two subscribing witnesses.

HERMAN H. BRANDES.
